UNITED STATES PATENT OFFICE.

HENRY M. PIERCE, OF GRAND RAPIDS, ASSIGNOR TO THE BANGOR CHEMICAL COMPANY, OF ELK RAPIDS, MICHIGAN.

AUTOMATIC COOLER FOR KILNS.

SPECIFICATION forming part of Letters Patent No. 243,302, dated June 21, 1881.

Application filed March 10, 1881. (No model.)

To all whom it may concern:

Be it known that I, HENRY M. PIERCE, a citizen of the United States, residing at Grand Rapids, in the county of Kent and State of Michigan, have invented certain new and useful Improvements in Automatic Coolers for Kilns, &c.; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 In the drawing is shown a vertical sectional view of devices embodying my invention.

My invention has for its object to save time and labor, to increase the working capacity of the apparatus employed, and consequently to 20 reduce the capital required for various manufacturing purposes, such as the manufacture of charcoal, lime, &c., or wherever, as is well understood, the contents of kilns, furnaces, and heating-chambers are preferably or necessarily 25 cooled out of contact with the air. The principle involved—viz., causing the circulation of cooled or refrigerated non-combining gases through kilns, furnaces, &c.—forms the subject-matter of an application filed by me December 21, 1880. The present invention therefore relates only to apparatus adapted to that purpose.

To this end it consists, mainly, in the combination, with a kiln or equivalent chamber, 35 of an eduction-pipe for conducting the heated gases, &c., from the kiln, a cooler for reducing the temperature of the gases, and an induction-pipe for reconducting the cooled or refrigerated gases to the kiln or furnace, the cooler 40 being so placed with relation to the furnace that the circulation of the gas, &c., is rendered automatic.

I will first proceed to describe the simplest and most practicable form of the invention and 45 a specific application thereof, not, however, intending to limit myself thereby, and will then point out modifications and additional features that may be employed, if desired. For the purposes of this description I have shown the 50 devices applied to a charcoal-kiln.

A indicates a charcoal-kiln, provided at or

near its base with a flue, *a*, which, during the charring of the wood, serves for the collection and escape of the gases, &c., developed.

Within the kiln, and at or near the top thereof, I arrange a perforated pipe or flue, *B*, from which extends a conduit or eduction-pipe, *B'*, leading to a cooler, *C*, preferably placed on top of the kiln, but at any rate so located with relation to the kiln that the cooled gases will 55 flow back thereto. Within the pipe *B* is a suitable valve, *b*, for arresting the flow of gas, &c., to the cooler.

Instead of using a perforated pipe, *B*, the flue may lead directly from the top of the kiln 60 to the cooler, as indicated by dotted lines *R'*; and instead of leading the conduit *B'* to the bottom it may enter at the top of the cooler, as indicated by dotted line *S*.

C indicates a cooler, which may be of any 70 desired pattern; but as I have shown a special construction adapted for use where a stream of running water is obtainable, I will for the sake of clearness describe it more particularly. This cooler is composed of an outer 75 box or tank for the reception of water or other cooling medium. Said box has a water-inlet, *c*, and an exit or overflow, *c'*, above, and is preferably divided up by horizontal partitions, *p*, which extend partially across the box from opposite ends alternately, so as to give the water or other cooling medium a zigzag course. Within said box or tank is arranged the gas-receptacle *G*, connected at one end with the pipe *B'*, which brings the gas from the kiln, 85 and at the opposite end with the pipe *D*, which reconducts the cooled gas to the kiln. This receptacle *G* is composed of two chambers, the one, *g*, being a receiving-chamber and the other, *g'*, a discharging-chamber, and these two chambers are connected by tubes *g²*, which serve to break up the body of gas, &c., and present it most advantageously to the cooling medium. The connecting-tubes *g²* are preferably inclined from the receiving to the discharging chamber, 90 so as to direct any condensed liquids to the trap *t*, arranged in the discharging-chamber. From the discharging-chamber *g'* a pipe, *D*, provided with a suitable valve, *d*, leads to the flue *a* at the bottom of kiln *A*.

When it is necessary or desirable to retain the cooling medium in instead of causing it to

circulate through the tank C, the partitions *p* may be omitted.

The operation of such devices will be as follows: The charring of the wood (or other operation conducted in the kiln) having been completed, the kiln or furnace is, as far as practicable, hermetically closed, the valves *b* and *d* opened to establish communication between the cooler and kiln, and the cooling medium admitted to tank C. The heated gases, &c., from the kiln A will then enter the perforated pipe or flue B, and pass thence by B' to the cooler, where their temperature will be reduced, and whence they will flow through pipe D into flue *a*, thence into the kiln A, where, becoming again heated by absorbing the heat from the contents of the kiln, they rise to the top of the kiln, enter pipe B, and establish an automatic circulation, which will continue until the temperature of the contents of the kiln is so reduced that a stasis is established.

The following modification in the arrangement and construction of the devices may be made, if desired: A series of kilns, A, may be connected with a single cooler by connecting the valved pipes B and D to mains common to all, and connecting the cooler with said mains, instead of directly to the induction and education pipes of a single kiln. In this manner the kilns may be cooled in succession by means of a single cooler located above the level of the kilns.

I will now describe additional features which may be employed at will.

Where running water is not readily attainable, it may become desirable to cause a circulation of the cooling-liquid through tank C by other means, in which case the following devices may be used: A chambér or tank, R, is provided and connected with the tank C by suitable pipes, *r' r'*, on one of which, if desired, a pump, P, can be arranged. When ice is used the same can be put in tank R and the cooling medium caused to circulate over and around it. When a freezing-mixture is employed, receptacles therefor may be arranged in tank R, and when the expausion of air or gases, &c., is

employed the tank R may contain expansion-cells and the circulating liquid may be brine, all of which is well known to persons skilled in the art; or, if desired, the cooler C itself may be one wherein the expansion of a gas is employed (as in well-known ice-machines) as a means of cooling. The simplest and most practical form is, however, that first described, and what follows is a mere refinement, too expensive and complicated for general use in manufacturing, where much has to be committed to unskilled labor, and is only introduced to indicate the scope of the invention.

I am aware that in utilizing the non-condensable gases developed in the manufacture of charcoal a kiln has been connected with a condenser and cooler placed above the same, and that the condenser has had an education-pipe leading to and delivering the uncondensed gases to a fire-chamber, in order that the gases might be burned, and that the heated products of such combustion were then permitted to enter the kiln to assist in the charring of the wood, and do not herein claim such subject-matter, for the reason that if the gas, after passing from the cooler, is ignited, as would be the case where it was passed through a fire-chamber, the heat developed would defeat the purposes of my devices.

Having thus described my invention, what I claim, and desire to secure by Letters Patent, is—

The combination, with a kiln, furnace, or heating-chamber, of an education-pipe leading from at or near the upper part of the kiln, a cooler located above the level of the kiln or furnace, and an induction-pipe leading from the cooler to the kiln, whereby an automatic circulation of a cooling-gas through the kiln or furnace can be established and maintained, substantially as and for the purpose specified.

In testimony whereof I affix my signature in presence of two witnesses.

HENRY M. PIERCE.
